United States Patent Office.

THOMAS MAHER, OF CLEVELAND, OHIO.

Letters Patent No. 95,919, dated October 19, 1869.

IMPROVEMENT IN CORE-BOX FOR CAR-WHEELS.

The Schedule referred to in these Letters Patent and making part of the same.

To all whom it may concern:

Be it known that I, THOMAS MAHER, of Cleveland, in the county of Cuyahoga, and State of Ohio, have invented certain new and useful Improvements in Core-Boxes for Making Cores for Car and similar Wheels; and I do hereby declare that the following is a full and complete description of the same, reference being had to the accompanying drawings, making a part of this specification, in which—

Figure 1 is a perspective view.

Figure 2 is a vertical section.

Like letters refer to like parts.

The nature of this improvement relates to a core-box for making cores for car and similar wheels, by which a perfect core can be made with simplicity and by ordinary skill.

By the old method of making cores, which is by filling a core-mould with the core-material, and then by forming the upper side of core by a sweep, it has been very difficult to produce a true core, which, when used, would very frequently make an imperfect casting, one side of the wheel often being thinner, makes a weak place, and rendering them liable to break.

The object of this improvement is to overcome the difficulties and liabilities above mentioned.

In the drawings—

A represents the lower half of a core-box, having a flange, *a*, and is provided with a suitable number of holes, *b*, for forming the supports on which the core is to rest when in the mould.

In the centre is provided a projection, *B*, which makes the central opening in the core.

C represents a cover or upper half of the core-box, and is provided with a flange, *d*, there being a rabbet in the flange *a*, to receive the shoulder on the flange *d*, which insures its fitting closely in place.

There is also a hole, *e*, in the centre, somewhat larger than the projection *B*.

A small sweep, *D*, is provided, which has a pin, *f*, fitting in a hole in the projection *B*, and in which it turns.

The operation of this improved box is as follows:

The bottom of the box *A* is first filled with the core-material, and packed or rammed down; and then the cover *C* is placed on, and secured by clamps, and more material is put in through the hole *e*, and rammed in compactly, filling the interior space. The sweep *D* is put in place, and, by giving it a few revolutions, the space is cleaned, and the core is finished, ready for use.

By this means a perfect core is made, and will insure an even thickness in casting car-wheels.

What I claim as my improvement, and desire to secure by Letters Patent, is—

The core-box *A*, cover *C*, and sweep *D*, constructed and arranged substantially as described.

THOS. MAHER.
